UNITED STATES PATENT OFFICE.

RICHARD DITTKIE, OF CHICAGO, ILLINOIS.

DESIGN FOR AN ILLUMINATED SIGN.

40,262.

Specification for Design.

Patented Sept. 14, 1909.

Application filed June 5, 1909. Serial No. 500,442. Term of patent 7 years.

To all whom it may concern:

Be it known that I, RICHARD DITTKIE, a subject of the Emperor of Germany, residing at Chicago, in the county of Cook and State of Illinois, have invented a new, original, and ornamental Design for an Illuminated Sign, of which the following is a specification, a reference being had to the accompanying drawing, forming a part thereof.

The figure is a view in elevation of an illuminated sign, showing my new design.

I claim:

The ornamental design for illuminated sign as shown.

RICHARD DITTKIE.
